poration of Ohio

Application April 30, 1935, Serial No. 56,626

Term of patent 14 years

To all whom it may concern:

Be it known that I, Harry Bregman, a citizen of the United States, residing at Lorain, in the county of Lorain and State of Ohio, have invented a new, original, and ornamental Design for Play Wagon or Similar Article, of which the following is a specification, reference being had to the accompanying drawing, forming a part thereof, in which

Fig. 1 is a side perspective view;

Fig. 2 is a rear end perspective view, and

Fig. 3 is a front end perspective view.

The design comprises a play wagon in which

the body is given an oval appearance. The front of the wagon is given a hooded appearance, concealing the front axle and the front wheels. The rear end of the wagon is also given a hooded effect, concealing the rear axle and the rear wheels, and the appearance is such that the hooded effect appears as an extension of the rear end of the body, the general appearance presenting a stream-line effect.

I claim:

The ornamental design for a play wagon or similar article as shown and described.
